SPRING FOUNDATION

Morris Lewittes, New York, N. Y., assignor of one-eighth to David Lewittes, one-eighth to Charlotte Lewittes, one-eighth to Israel Lewittes, one-eighth to Sarah Lewittes, one-eighth to William Lewittes, one-eighth to Bertha Lewittes, and one-eighth to Fannie Lewittes, all of New York, N. Y.

Application February 24, 1945, Serial No. 579,597

3 Claims. (Cl. 155—179)

1

This invention relates to spring foundations. It is particularly directed to a spring seat for upholstered furniture.

In spring seats having coil springs, the springs have hitherto been tied to each other and to the frame with tie-cords. These tie-cords very often tear and are difficult to attach in place. It is therefore an object of this invention to provide a spring seat for upholstered furniture having improved means for attaching the coil springs on the webbing to each other and to the frame.

Another object of this invention is to provide a spring seat of the character described having ribbons or strips of textile material over the tops of the coil springs, said strips being attached to the top convolutions of the coil springs by rings or clips and the ends of these strips being attached to the walls of the seat frame.

Another object of this invention is to provide a spring seat of the character described having improved means for pulling down the attaching strips at the front end of the frame for tensioning said strips.

Yet another object of this invention is to provide a highly improved spring seat construction of the character described which may be applied to either hard edge or soft edge seats, and which shall be relatively inexpensive to manufacture, easy to apply, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a top plan view of a spring seat embodying the invention;

Fig. 2 is a cross-sectional view taken on line 2—2 of Fig. 1;

Fig. 3 is a cross-sectional view taken on line 3—3 of Fig. 2;

Fig. 4 is a partial perspective view of the inner side of the front wall of the spring seat frame illustrating a part of the construction;

2

Fig. 5 is an enlarged partial perspective view showing crossing strips attached to the top convolutions of a spring;

Fig. 6 is a top plan view of a spring seat embodying the invention and illustrating a soft edge spring seat construction;

Fig. 7 is a cross-sectional view taken on line 7—7 of Fig. 6; and

Fig. 8 is a cross-sectional view taken on line 8—8 of Fig. 7.

10 Referring now in detail to the drawing, 10 designates a spring seat construction for upholstered furniture embodying the invention. The same comprises a frame 11 having a front wall 12, a rear wall 13, and side walls 14. The frame may be supported on front legs 15 and rear legs 16. Attached to the underside of the frame is a webbing 17. The webbing 17 may be a piece of burlap attached at its edges to the underedges of the frame. On the webbing 17 are 20 a plurality of rows of coil springs 19.

Improved means is provided for attaching the coil springs to each other and to the frame. To this end there is provided a plurality of transverse strips 22 made of textile material. Strips 22 may be of canvas, burlap, twill, or any other stout textile material. Each strip 22 passes over the top of a row of springs 19. The ends of strips 22 are attached to the upper edges of side walls 14, as by nails 23 or the like attaching means. Each strip 22 is attached to a top convolution 26 of a coil spring 19 by means of hog rings or clips 27 which pass around the top convolution and through the strip. Preferably each strip is attached to one spring by a pair of rings 27 located at diametrically opposite sides of the top convolution of the spring, and at opposite edges of the strip.

There is furthermore provided a plurality of strips 30 extending from front to rear, one for each row of springs. The rear ends of the strips 30 are attached to the upper edge of the frame by nails or other fastening devices 33. Strips 30 pass over the tops of the coil springs 19 and over the strips 22, across the latter. Strips 30 are attached to the top convolutions of springs 19 also by means of diametrically opposed hog rings or clips 38. Each strip 30 is attached to one of the springs by a pair of clips 38 passing around the top convolution of the spring and through op-

posite edges of the strip. The front end of strips 30 are attached to the upper edge of front wall 12 by nails or any other fastening means 40.

Means is provided for tensioning the strips 30 adjacent the front wall 12. To this end there is attached to the inner surface 12a of front wall 12, a horizontal strip 50 likewise made of textile material. The strip 50 passes over each of the strips 30 and is attached to the wall 12 by nails or other fastening devices 51 at opposite sides of each strip 30. The strip 30 is thus looped and pulled downwardly as at 52 in front of wall 12 so as to tension strip 30.

The strips 22 and 30 being flat and wide, make a good bearing surface for padding placed over the springs. The strips 30 are preferably about one inch in width. They could be between one-half inch and one and one-half inches, if desired.

The spring construction shown in Figs. 1 and 2 is a hard edge spring construction. In Figs. 6, 7 and 8 is shown a soft edge spring construction embodying the invention. In Figs. 6, 7 and 8 there is shown a spring seat 60 comprising a frame 61 having a front wall 62, a rear wall 63, and side walls 64. The frame may be supported on front legs 65 and rear legs 66. Attached to the underside of the frame is a webbing 67. On the webbing 67 and within the frame are a plurality of rows of coil springs 69. The front row of springs 69 are close to the front wall 62. The front row of springs are also interconnected by an edge wire 70, attached to the frame as by brackets 71 and clipped to the upper convolutions of the front row of springs as by metal clips 72.

The rows of springs are attached together and to the frame by means of a plurality of strips 75 extending from front to rear. The rear ends of the strips 75 are attached as by nails 76 to the upper edge of rear wall 63. Strips 75 pass over the tops of the rear springs of each row and over the rear edge of the top convolutions of the front spring of said row. The strip 75 has a portion 77 passing down through the spring and then looped upwardly about strip 85 and extending at 78 over the top edge of front wall 62. Extending from portion 78 is a strip portion 79 which again passes upwardly and rearwardly through the spring and over the top of strip 75. Strip portions 78 are attached to the front wall by nails or other attaching means 80. The outer end of strip portion 79 is attached to strip 75 by hog rings 81 which pass around the rear sides of the top convolutions of the springs 69 at the front of the frame. Strip 75 is attached to the rear springs in each row by hog rings 83. The hog rings 83 are disposed at opposite sides of strip 75 and at diametrically opposed sides of the upper convolutions of the springs.

Means is provided to tension the strips 75 adjacent their front ends. To this end there is attached to the inner surface 62a of front wall 62 of the frame a horizontal transverse strip or ribbon 85 of textile material. Strip 85 has looped portions 86 looped over the loop portions 77 of the strips 75. Strip 85 is attached to the front wall by nails or attaching means 87 at opposite sides of the loops 86. Strip 75 is thus tensioned downwardly.

Means is provided to tie down the front portions of the upper convolutions of the springs 69 in the front row. To this end there is provided, for each of the front springs, a strip 90 having one end 91 attached to the upper edge of the front wall 62 by the attaching means 80.

Strip 90 passes over the edge wire 70 and over the top of the front spring 69 and is attached to the strip portions 77 and 75 by said hog rings 81.

Transverse strips 95 are also provided for each transverse row of springs. Said strips 95 have the ends thereof attached to the side walls 64 of the frame by attaching means 96. The strips 95 overlie the rows of springs 69 and cross the strips 75 and are attached to the top convolutions of the springs by hog rings 97. The strips 95 are attached to each spring by a pair of hog rings 97 located at opposite edges of the strip and at diametrically opposed portions of the spring.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A spring seat comprising a horizontal frame, a webbing secured to and disposed substantially in the plane of the bottom of the frame, a plurality of rows of coil springs on the webbing and projecting above said frame, transverse strips overlying the top convolutions of the springs, means to attach the ends of the strips to the side walls of the frame, and strips running from front to rear and overlying the tops of the springs, means to attach the front and rear ends of the strips running from front to rear, to the front and rear walls of the frame, and means to tension the strips which run from front to rear, said tensioning means comprising a strip attached to the inner surface of the front wall of the frame and looped over the strips which run from front to rear.

2. A spring seat comprising a horizontal frame, a webbing secured to and disposed substantially in the plane of bottom of the frame, a plurality of rows of coil springs on the webbing and projecting above said frame, transverse strips overlying the top convolutions of the springs, means to attach the ends of the strips to the side walls of the frame, and strips running from front to rear and overlying the tops of the springs, means to attach the front and rear ends of the strips running from front to rear, to the front and rear walls of the frame, and means to tension the strips which run from front to rear, said tensioning means comprising a strip attached to the inner surface of the front wall of the frame, and looped over the strips which run from front to rear, said strips being made of textile material.

3. A spring seat comprising a horizontal frame, a webbing secured to and disposed substantially in the plane of the bottom of the frame, a plurality of rows of coil springs on the webbing and projecting above said frame, transverse strips overlying the top convolutions of the springs and running from side to side, means to attach the ends of the strips to the side walls of the frame, and strips running from front to rear and overlying the tops of said springs, means to attach the front and rear ends of the strips running from front to rear to the front and rear walls of the frame, and a single means arranged on the front

wall of the frame to permit selective tensioning of the strips which run from front to rear.

MORRIS LEWITTES.
